H. G. BUCHAN.

LOOSE LEAF BINDER.

APPLICATION FILED MAY 9, 1910.

1,053,970.

Patented Feb. 25, 1913.

UNITED STATES PATENT OFFICE.

HUGH GELLROY BUCHAN, OF NEWARK, NEW JERSEY.

LOOSE-LEAF BINDER.

1,053,970.

Specification of Letters Patent. Patented Feb. 25, 1913.

Application filed May 9, 1910. Serial No. 560,317.

To all whom it may concern:

Be it known that I, HUGH GELLROY BUCHAN, of the city of Newark, in the county of Essex and State of New Jersey, 5 have invented certain new and useful Improvements in Loose-Leaf Binders, of which the following is a specification.

The object of my invention is to provide a binder, especially adapted for binding a body of loose-leaves, signatures or pamphlets into a book, from which, when so bound, any one of such pamphlets, signatures or loose leaves, may be quickly and easily removed; and, if desired, new ones inserted in the place thereof, without disturbance of the others originally therein, by those authorized to make such changes; while at the same time, such leaves, signatures or pamphlets are fully protected 15 against any accidental or unauthorized removal or displacement; such binding being at the same time of extreme simplicity of mechanism, and operation, and one adapted to be manufactured at a minimum of cost.

25 To such ends, the said invention consists in substance, of a back-piece formed of two segmental shaped back-pieces formed of thin sheet-metal, longitudinally hinged together, in such manner that the forward 30 free moving-edges of the binder-back, formed thereby, when forced toward one another, will clamp the body of loose-leaves, signatures or pamphlets between such edges, so as to form such body into a single-book; 35 means for forcing the segments together into the binding position, and for locking the same therein; means for actuating such locking-means removable from the binder; a cover-strip hinged to each of the segments 40 at the binding-edge adapted to be secured to a cover-board; a cover-board secured to each of such cover-strips; an outer covering-sheet covering each cover-board and extending from one to the other over and around 45 the back-piece formed by the two hinged segments; end-shields secured to each of the segments at the ends for forming a protective closure of the back-piece when in the binding position; and securing-pins carried 50 by each of the segments hinged to the binding edge of their respective segments, so as to pass through the mass to be bound when the parts are in the binding position—those carried by one segment being preferably 55 hollow and inclosing those carried by the other segment when in the binding position,

in such manner that the axes of each pair of such co-acting-securing-pins are coincident, and the solid pins are each covered by its coacting hollow securing-pin. It is not 60 intended, however, to limit the said invention to a structure comprising at once all of said mentioned parts, as the same may be varied in construction in many ways, and I do not intend to limit myself, except as more 65 specifically and clearly set forth in the claims forming a part of this specification.

Said invention is fully shown and described in the following specification, of which the accompanying drawings forms a 70 part, wherein similar letters or numerals of reference designate like or equivalent parts wherever found throughout the several views, and in which;

Figure 1 is an end view in perspective of 75 my improved loose-leaf binder in the closed position; Fig. 2 is an end view of the rear or back-portion of such binder on an enlarged scale taken in cross-section, on the line *a—a* of Fig. 3, looking in the direction 80 of the arrow, and Fig. 3 is a plan view of the mechanism shown in Fig. 2 looking to the left in such Fig. 2, taken on the line *b—b*, the hinged-cover-plates being shown at the extreme right thrown back into the 85 open position, while one pair of the concentric securing-pins is shown in the closed or binding position in full lines, while a second pair of such pins is shown in dotted lines in the open or non-binding position. 90

Referring to the drawing:—The reference letter A designates the segmental shaped back-pieces, and B the side covers, of my improved form of loose-leaf-binder. The back-piece A is composed of two segmental shaped-pieces 1 and 1', formed of suitable sheet-metal bent into proper form, secured together longitudinally at the rear center by a hinge-joint 2, formed either by a suitable hinge riveted thereto, or of hinge-coils formed integral from the two sheets, through which passes the hinge-rod 3; and on the forward open moving or binding edges 4 of the segments 1 and 1' are hinged in like manner by means of a hinge-rod 5, cover strips or plates 6, also of thin sheet-metal, which are firmly secured to the cover-boards 7 by suitable rivets 8, or other suitable means. Also hinged to the hinge-rod 5 on one side are a plurality of hollow-securing-pins 9, each of which incloses a 105 slightly smaller diametered securing-pin 110

10, which, when the parts are in the binding position, lie within the same, and both within a seat or perforation 11 in the rear edge of the body of leaves, to be bound; 5 which pins 10 are hinged in like manner to the other segment 1' by its hinge-rod 5.

Secured usually by glue to the outer side of each of the cover-boards 7 is an outer cover-sheet 12, usually of leather or other 10 suitable fabric, which usually extends around and over the segmental back A, so as to form the back-cover-strip 12'; and secured within each of such cover-boards 7, usually in the same manner, is the inner 15 cover-sheet 13, of any suitable material such as cloth or leather.

Secured to the segmental shaped piece 1' of the back-piece A, within the same, are two supporting lugs 14 in and between 20 which is firmly secured the slide-rod or bar 15, carrying two slide-blocks or gibs 16 and 16', which slide freely back and forth thereon. Secured in like manner to the other segmental shaped piece 1 are three journal-lugs 17 in which is revolubly supported the 25 screw lock-rod 18; which is provided with two screw-threaded sections 19 and 19', one of which is of right and the other of left hand thread, upon each of which screw-sections is threaded a nut-block or gib, 20 and 20'. The lock-rod 18 is preferably provided at the outer end with a square-shouldered portion 21, upon which may be fitted the removable locking-key 22, by which 35 such lock-rod 18 may be rotated in either direction.

Secured by suitable screw-pivot-bolts 23, to the slide-blocks or gibs and also to the 40 nut-blocks or gibs are two actuating-levers 24 and 24', pivoted together at their common centers by a pivot-bolt 25. The lever 24 being pivoted at one end to the slide-block or gib 16, and at the other to the nut-block or gib 20', while the lever 24' is secured in like manner to the slide-block or 45 gib 16', and the nut-block or gib 20. By this arrangement, it will be seen that the two actuating-levers 24 and 24', when so connected, form a compound or lazy-tongs 50 lever D, which will draw the two segments 1 and 1' together into the binding position shown in full lines, when the lock-rod 18 is rotated so as to force the nut-blocks or gibs 20 and 20' apart; and which will force 55 such segments into the open position, shown in dotted lines, when such lock-rod 18 is rotated in the reverse direction, so as to draw the nut-blocks or gibs 20 and 20' together; and when in such fully open position, the securing pins 10 are fully drawn 60 out and disengaged from the coacting hollow-securing-pins 9; and both may then be thrown back upon their respective hinges into the position shown in dotted lines in 65 Fig. 3, when even though the body of leaves

bound may be provided with securing perforations to receive such securing-pins, such body may be at once easily removed. In cases where such body of leaves is instead of perforations, provided with slots 70 open to the rear, it will of course never be necessary to disengage the securing-pins from each other, inasmuch as as soon as the leaves are released from the binding pressure of the binding edges at 4. of the 75 segments, they can then easily be drawn out.

In order to protect the ends of that portion of the body of leaves bound, located within the segmental back formed by the pieces 1 and 1', to each of such pieces 1, is 80 secured in any desired manner, usually by means of rivets 30, protecting end-plates 31 and 32, usually of thin-sheet-metal, and of substantially the shape shown; and when the binder is in the closed position, overlapping at the center, as shown in dotted lines in Fig. 2, to permit the insertion of the actuating-key 22, the plate 32 is provided with a suitable key perforation or slot 21. 85

I claim:—

1. In a binder, a hinged back-piece, mechanism for forcing the back-piece into the open and closed positions, a cover-plate extending substantially the full length of each of the back-pieces secured to the forward binding edge thereof by a hinge-joint which forms the compressing points of contact of the back-piece with the body of leaves to be bound, a cover-board secured to each cover-plate, and an outer flexible covering-piece 90 secured to each of the cover-boards and extending around and over the hinged back-piece. 95

2. In a binder, a hinged back-piece, mechanism for forcing the back-pieces into the open and closed positions, a cover-plate hinged to the forward binding edge of each segment of the back-piece, and securing-pins adapted to pass through the body of leaves to be bound also hinged to the forward-binding-edge of each of the segments or back-pieces forming the hinged-back. 105 110

3. In a binder, a hinged back-piece, mechanism for forcing the back-pieces into the open and closed positions, a cover-plate 115 hinged to the forward binding edge of each segment of the back-piece, and securing-pins adapted to pass through the body of leaves to be bound also hinged to the forward-binding-edge of each of the segments 120 or back-pieces forming the hinged-back, the pins on one side being hollow and each inclosing its co-acting pin on the opposite segment of the back-piece when the parts are in the binding position. 125

4. In a binder, a back-piece formed of two segmental shaped pieces longitudinally hinged together, a cover-plate hinged to each segmental shaped piece at the forward or binding-edge thereof, a slide-bar secured 130

- longitudinally to one of such segmental shaped pieces, slide-blocks or gibs sliding on the slide-bar, a screw-lock-rod revolvably mounted within the other segmental-piece 5 provided with a right and a left-hand screw-thread, each having a threaded nut thereon, and a compound lazy-tongs lever connecting the thread-nuts with the slide-blocks.
- 10 5. In a binder, a back-piece formed of two segmental shaped pieces longitudinally hinged together, a cover-plate hinged to each segmental shaped piece at the forward or binding-edge thereof, a slide-bar secured 15 longitudinally to one of such segmental shaped pieces, slide-blocks or gibs sliding on the slide-bar, a screw-lock-rod revolvably mounted within the other segmental-piece provided with a right and a left-hand screw-thread, each having a threaded nut thereon, and a compound lazy-tongs lever 20 connecting the thread-nuts with the slide-blocks by suitable pivot joints.
6. In a binder, a back-piece formed of 25 two segmental shaped pieces longitudinally hinged together, a cover-plate hinged to each segmental shaped piece at the forward or binding-edge thereof, a slide-bar secured longitudinally to one of such segmental 30 shaped pieces, slide-blocks or gibs sliding on the slide-bar, a screw-lock-rod revolvably mounted within the other segmental-piece
- provided with a right and a left-hand screw-thread, each having a threaded nut thereon, and a compound lazy-tongs lever 35 connecting the thread-nuts with the slide-block by suitable pivot joints, and a removable key for rotating the screw-lock-rod.
7. In a binder, a back-piece formed of two segmental shaped pieces longitudinally 40 hinged together, a cover-plate hinged to each segmental shaped piece at the forward or binding-edge thereof, a slide-bar secured longitudinally to one of such segmental shaped pieces, slide-blocks or gibs sliding 45 on the slide-bar, a screw-lock-rod revolvably mounted within the other segmental-piece provided with a right and a left-hand screw-thread, each having a threaded nut thereon, and a compound lazy-tongs lever 50 connecting the thread-nut with the slide-blocks, and protective end-pieces over-lapping one another so as to form a covering for the ends of the back-piece, secured to each of the segmental back-pieces of the 55 back-piece at either end thereof.
- In testimony whereof I have signed my name to this specification in the presence of two subscribing witnesses.

HUGH GELLROY BUCHAN.
